WIPER MEANS FOR LASTING MACHINES
 Raymond M. Bowler, Salem Depot, N.H., assignor to
 United Shoe Machinery Corporation, Boston, Mass., a
 corporation of New Jersey

Filed Oct. 4, 1963, Ser. No. 313,965
 6 Claims. (Cl. 12—12.4)

This invention relates generally to machines for lasting shoes and more particularly is directed to an improved mechanism for operating the lasting wipers embodied in such machines.

To obtain optimum lasting results, especially on the forepart region of a shoe, it is important that the wipers adapted to engage the upper in this region be properly oriented so as to effect competent wiping simultaneously at all points along opposite sides of the forepart of the shoe. Ideally, the wipers should conform generally to the shape of the last around the entire forepart of the shoe and be moved inwardly over the shoe bottom substantially at right angles to the edge of the insole.

Machines presently available for this operation have the wipers disposed for equal movements from positions equally spaced from the center line of the machine. The wipers themselves have been generally shaped to give optimum results when utilized with regularly shaped shoes, that is, shoes not having either extremely square or pointed foreparts. When operating on shoes of the usual sizes and shapes such wiper configuration and movement affords substantially adequate wiping along all points of the forepart of the shoe. However, when shoes having square or pointed foreparts are lasted there is necessarily considerable compromise with the ideal wiper movement for the sake of effecting a minimally adequate wiper motion along the whole of the margin of the forepart. Wipers specifically adapted for operating on such shoes may be used to replace the more regularly shaped wipers but the motion of the wipers generally remains the same. There have been modifications to lasting machines to allow altering of the motion of one or both wipers to effect wiping coverage which would otherwise not be had. However, even where a particular motion, such as an extended wiping on one side, has been introduced, and a special configuration of wiper has been used, the range of sizes and styles of shoes on which an adequate operation can be performed by a single pair of wipers is extremely limited.

Particular problems existing in certain areas of lasting, mentioned by way of example, include the square toe of a work shoe, the relatively square toe and size of an infant's shoe forepart, and the narrow forepart and pointed toe of some styles, particularly in women's shoes. Another area where difficulties exist is in the lasting of welt shoes, where a particular movement of the wipers is desired so that the upper will be pressed uniformly against the insole rib. The problem of welt shoes, furthermore, is not restricted to unusual shapes of shoes.

According to a feature of this invention, individual adjusting means are provided in a lasting machine for the operating mechanisms of each of its wiper carriers to impart a variable motion to each wiper so as to accommodate an infinite variety of forepart sizes and styles, and to afford wiping movement to the extent desired and at angles relative to the edge of the insole more nearly approximating the ideal than has heretofore been possible.

The above and other features of the invention, including novel details of construction and arrangement of parts, will now be more particularly described with reference to the accompanying drawings and pointed out in the claims.

In the drawings,

FIG. 1 is a plan view with parts broken away and part-

ly in section of the wiper means of a portion of a lasting machine embodying the present invention and showing the wiper operating mechanism and adjusting mechanism.

5 FIG. 2 is a detail side elevation partly in section of the wiper means with some parts omitted for clarity; and

FIG. 3 is a section substantially along line III—III of FIG. 1.

The wiper means of the present invention may be embodied in a lasting machine of the type shown in an application for United States Letters Patent of Raymond M. Bowler et al., Serial No. 194,064, filed May 11, 1962, to which reference may be had for details relative to the construction and operation of a typical machine to which the invention may be applied. However, it should be understood that the invention is not limited in respect of its applicability to machines of that particular type and, instead, is equally applicable to lasting machines of other types adapted to operate on either the forepart or the heel end of shoes.

10 The improved wiper means illustrated in the drawings includes a pair of wipers 2 and 4 mounted in a pair of carriers 6 and 8, respectively, which are slidably received in a wiper head 10 between a frame member 12 and a cover plate 14. The carriers 6, 8 are provided with cam rolls 20, 22, 24 and 26 mounted on pins extending upwardly from the carriers 6, 8. The rolls are received in cam slots 30, 32, 34 and 36 in the underside of the cover plate 14 to guide the carriers 6, 8 and wipers 2, 4 in their advancing and closing movements.

15 The carriers 6, 8 are connected, respectively, by links 40, 42 to levers 44, 46 which are pivotally disposed on fulcrums 48, 50 secured to the cover plate 14. The cover plate 14 is urged rearwardly (i.e. upwardly as viewed in FIG. 1) by two springs 52, 54 extending from opposite rear corners of the cover plate 14 to pins upstanding from the frame 12. A cross bar 56 fixed to the end of a rod 58, which extends forwardly from a mover (not shown) is adapted to engage an after face of the cover plate 14.

20 Fixedly attached to the frame 12 are guide members 60, 62 slidably retaining the cover plate 14. Brackets 64, 66 are secured to the guide members 60, 62, respectively, and pivotally support studs 65, 67 which rotatably and pivotally support shafts 68, 70. The forward ends of the 25 shafts 68, 70 are provided with knurled knobs 72, 74. The rearward ends of the shafts 68, 70 are threaded into lugs 76, 78 which mount pins 80, 82 slidably disposed in slots 84, 86 in the levers 44, 46. The pins 80, 82 each have an enlarged cap portion as at 83 (see FIG. 3).

30 Partially threaded shafts 88, 90 having knurled knobs 92, 94 at their nonthreaded ends, are disposed along the center line of the unattached arms of the levers 44, 46 and are rotatably retained in threaded bores 96 passing through the fulcrums 48, 50. The shafts 88, 90 are rotatable in the enlarged cap portion 83 of the pins 80, 82 but are not movable axially relative to the pins 80, 82. Referring to FIG. 3, it may be noted that the shaft 90 is provided with a groove 79 receiving a pin 81 which prevents axial movement of the shaft 90 in the cap 83.

35 40 A detailed description of the adjusting mechanism and its method of operation follows. For the sake of simplicity reference will be made to the right side wiper 4, it being understood that the left side wiper and its associated mechanism operate in the same manner.

45 In preparing the wipers for operation, the operator adjusts the knobs 94 and 74 to position the wiper 4 in accordance with the size and contour of the shoe and the wiping motion to be applied to it.

50 Assuming for purposes of explanation that an extended wiper motion is desired of the right side wiper 4, the operator turns the knob 94 in a clockwise direction. The pin 82 is moved in the slot 86 toward the fulcrum

50, decreasing the length of the lever to the left of the pin 82. The length of the lever 46 of the pin 82 determines the extent of the wiping motion of the right forepart wiper 4.

To orient the wiper 4 properly relatively to the last, the operator adjusts the knob 74. By rotating the knob 74 in a counterclockwise direction the operator causes the lug 78 to be moved rearwardly along the axis of the shaft 70 on the threads of the shaft 70. The lug 78 carries the pin 82 rearwardly with it, causing the lever 46 to pivot about the fulcrum 50. The pivotal motion of the lever 46 carries forward the end of the lever 46 attached to the link 42, transmitting through the link a forward movement to the wiper carrier 8, thereby causing the cam rolls 24, 26 to ride forwardly in the cam slots 34, 36. The forward movement of the cam rolls 24, 26 in the cam slots 34, 36 causes a commensurate change in the position of the wiper 4, in this instance a closing motion. Thus, the knob 74 is used to enter initial angular adjustments.

Having adjusted both knobs 94 and 74 for the right side wiper 4, the same type of adjustments may be entered for the left side wiper 2 with the like use of the knobs 92 and 72. A gauge comprised of reference marks may be incorporated in the levers 44, 46 and in the frame member 12 for use in conjunction with knobs 72, 74, 92, 94 for quick and easy setting of the adjustments.

By activation of a treadle (not shown) the rod 58 is driven forward causing the bar 56 to engage the rear face of the cover plate 14. The cover plate 14 is thereby driven forward against the influence of springs 52, 54, effecting a forward movement of the cam slots 30, 32, 34, 36. As the cover plate 14 moves forward, the fulcrum 50 is carried forward with it, the description again being restricted to right side operation. The pin 82 is now stationary and acts as a fulcrum about which the lever 46 pivots. The lever 46, pivoting about fixed pin 82 and the moving fulcrum 50, moves the link 42 and thereby also moves the wiper carrier 8 and wiper 4 to an extent dependent upon the length of the lever to the left of the stationary pivot point, the pin 82. After completion of the wiping operation, the rod 58 returns to its initial position and the springs 52, 54 urge the cover plate rearwardly, returning the fulcrum point 50 to its original position.

If a different size of shoe is to be operated upon, the knobs 72, 74 are operated to adjust the positions of the wipers 2, 4 to suit the size of the shoe. An extended wiper setting may be entered through the knobs 92, 94. In order to change from a left shoe operation to a right shoe operation it is only necessary to reverse the settings of the right and left side knobs.

The above described adjustments provide a wiping means selectively adjustable to various sizes and shapes of shoes and afford an improved angle of approach of the wipers relative to the edge contour of the insole. Further, by the use of these adjustments, the wiping of welt shoes is facilitated in that the extent of the wiping action and the orientation of the wipers is easily and accurately controlled.

Having thus disclosed my invention and described in detail the preferred embodiment thereof, I claim as new and desire to secure by Letters Patent of the United States:

1. In a machine for lasting shoes, wiping means com-

prising wipers, wiper carriers retaining the wipers, a reciprocating cover plate having means for guiding the wiper carriers in opening and closing directions, means for selectively and individually varying the extent of the closing motion of each wiper carrier, and means for selectively varying the initial position of each wiper carrier thereby to vary the positions of the wipers individually to accommodate various sizes and styles of shoes.

2. The invention according to claim 1 in which the means for effecting the extent of the closing motion comprises an individually adjustable lever and linkage means for each wiper.

3. The invention according to claim 2 in which the lever and linkage means include a lever having a pivot point which may be selectively positioned to vary the effective length of the lever.

4. In a machine for lasting shoes, wiping means comprising wipers, wiper carriers retaining the wipers, a reciprocating cover plate having means for guiding the carriers in opening and closing directions, means operated by reciprocation of the cover plate for moving the carriers in said directions, means for selectively varying the extent of the closing motion of each wiper carrier including a lever having means for varying its effective length, and means for varying the initial position of the lever for selectively positioning each wiper thereby to accommodate various sizes and styles of shoes.

5. In a machine for lasting shoes, wiping means comprising a pair of wipers, a pair of wiper carriers retaining the wipers and having cam rolls attached thereto, a reciprocating cover plate having cam slots for guiding the cam rolls in a closing direction, a mechanism for moving each wiper carrier in said direction comprising a fulcrum fixed to the cover plate, a lever pivotally mounted upon the fulcrum, linkage means connecting the lever to the wiper carrier, a selectively adjustable pivot on the lever, means for locating the pivot along the lever to vary its effective length, and means for selectively locating the pivot relative to the path of reciprocation of the cover plate to vary the initial position of the lever.

6. In a machine for lasting shoes, wiping means comprising a pair of wipers, a pair of wiper carriers retaining the wipers and having cam rolls attached thereto, a reciprocating cover plate having cam slots for guiding the cam rolls and hence also the wiper carriers in a closing direction, a mechanism for each wiper carrier comprising a fulcrum fixed to the cover plate, a lever pivotally mounted on the fulcrum, a link connecting one end of the lever with the wiper carrier, a pin slidably disposed in a slot in the other end of the lever, a threaded shaft engageably rotatable in the fulcrum and rotatable but retained against axial movement in the pin, and a second mechanism for each wiper carrier comprising a bracket, a second threaded shaft pivotally and rotatably supported by the bracket and rotatably engaging a lug to which is attached the pin.
